US00D532410S

(12) **United States Design Patent** (10) **Patent No.:** **US D532,410 S**
(45) **Date of Patent:** **** Nov. 21, 2006**

(54) **MICROPHONE**

(75) Inventor: **Minoru Shimizu**, Tokyo (JP)

(73) Assignee: **Sony Computer Entertainment Inc.**,
Tokyo (JP)

(**) Term: **14 Years**

(21) Appl. No.: **29/242,850**

(22) Filed: **Nov. 16, 2005**

(30) **Foreign Application Priority Data**

Jul. 15, 2005 (JP) D2005-020783

(51) **LOC (8) Cl.** **14-01**

(52) **U.S. Cl.** **D14/226**

(58) **Field of Classification Search** D14/225,
D14/226, 227, 228, 229, 142, 155, 433; D10/104;
D13/147; 181/158, 242; 379/430, 431, 432;
381/111, 122, 174, 355, 369
